UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

RADIATOR

Application filed October 7, 1929. Serial No. 397,877.

The invention relates to a cooling device for cooling the lubricant and also the cooling liquid of a motor.

The invention has as one of its principal objects the provision of means for accomplishing the above objects, which means is particularly adapted for association with a vehicle conveyance or railway car employing a cooling medium for the motor.

10 A further object of the invention is the provision of a heat exchange device arranged in the circulating system of the cooling medium of the engine and the combination therewith of a heat exchange device for the 15 lubricant of the motor, the heat exchange devices being arranged to accomplish circulation of the lubricant and cooling medium and to subject both the lubricant and cooling medium to an air current to thus efficiently 20 dissipate the heat of both the lubricant and the cooling medium and cause it to be returned to the motor in a cooled condition.

A further object of the invention is the provision of means for forcing air through 25 heat exchange devices and to arrange said heat exchange devices and said means within a chamber to thereby cause circulation of air through the heat exchange devices.

The invention also has as an object combining and arranging the various elements entering into the structure so that a simple and efficient construction is produced.

The invention will be explained and more readily understood when read in conjunction 35 with the accompanying drawings which illustrate various embodiments of which the invention is susceptible, it being therefore obvious that other changes and modifications may be resorted to without departing from 40 the spirit of the appended claims forming a part hereof.

In the drawings, Fig. 1 is a side elevation of an end of a street or railway car having the invention applied thereto;

45 Fig. 2 is a plan view of the device shown in Fig. 1;

Fig. 3 is a section taken on line 3-3 of Fig. 2;

50 Fig. 4 is a section taken on line 4-4 of Fig. 1;

Fig. 5 is a section taken on line 5-5 of Fig. 2;

Fig. 6 is a section taken on line 6-6 of Fig. 5;

Fig. 7 is a plan sectional view of one end 55 of the element employed in the structure shown in Fig. 1;

Fig. 8 is a sectional view of a fragment of one of the heat exchange devices shown in Fig. 7;

Fig. 9 is a sectional view of the opposite end of the structure shown in Fig. 8;

Figs. 10 and 11 are respectively side and plan views of a modified structure which may be utilized to accomplish features of the invention; and

Fig. 12 is another modification.

The invention is illustrated as associated with a street or railway car generally designated 10 which employs an internal combustion engine generally designated 11 as the motive power for the car. The device whereby the lubricant and the cooling medium for the motor 11 is cooled is generally designated 12 and is, in the adaptation thereof shown 70 in Fig. 1, applied to the roof of the vehicle or car 10. The water jacket of the motor 11 has one end of a pipe line or extension 13 attached to it, the opposite end of the pipe 13 being connected with a tank 14, the latter 80 of which, in turn, is connected with the upper end of an inclined radiator or heat exchange device 15 to which a return pipe 16 is connected, the opposite end of the pipe being attached to the water jacket of the motor 11. 85 From this it will be seen that as the cooling medium or water contained in the jacket of the engine 11 becomes heated, it will rise, flow through the pipe 13, be discharged into the tank 14, gravitate through the heat exchange device or radiator 15 and be returned 90 through the medium of the pipe 16 to the water jacket of the engine, thus producing circulation thereof and cooling during circulation.

A pipe connection 17 is provided 95 which may have one end thereof connected with the oil sump or some other suitable portion of the oiling or lubricating system of the engine 11. This pipe 17 has the opposite end thereof, such as 18, connected with the pipe 100

connections generally designated 19 which feed the heated oil rising in the pipe 17 to the heat exchange devices respectively designated 20, 21, 22 and 23 (see Fig. 2). Pipe 5 connections 24 are formed between these heat exchange devices just referred to and a pipe connection 25. This pipe connection 25 extends from the connections 24 and has its opposite end attached with the engine 11 and 10 completes a system for conveying oil from the engine 11 to and through the heat exchange devices and back to the engine. From this it can be seen that a means is provided 15 for cooling both the cooling medium for the engine and the lubricant therefor.

The invention contemplates the provision and utilization of a means for producing air currents, forcing and directing these air currents through the radiators above referred 20 to, to thereby facilitate cooling of the cooling medium for the engine and the lubricant therefor. This means includes power operated or air current inducing fans respectively designated 26 and 27 which are 25 designed to be driven by a motor 28, preferably electric, and are arranged or located between the heat exchange devices generally designated 20, 21, 22 and 23 and the heat exchange device generally designated 15. These fans 30 and heat exchange devices are arranged with respect to each other so that a current of air induced by the fans is caused to travel through the radiator or heat exchange devices 15, 20 to 23 and be discharged from a 35 casing generally designated 29 in which the motor 28 and said fans are housed. The motor 28 is mounted upon a standard 30 which holds the motor with respect to other portions of the structure.

40 By referring to Fig. 2 it will be seen that the heat exchange device generally designated 15 is composed of a plurality of separate heat exchange devices 31 and by referring to Fig. 5, the manner of mounting these 45 separate heat exchange devices will be seen. As illustrated in Fig. 5, it will be noted that the tank 14 has a longitudinally arranged and laterally extending tubular part 32 and that the lower wall of this tubular portion 50 32 is provided with one or more apertures such as 33 through which communication is afforded with the interior of the tank 14. Each of the heat exchange devices 31 have 55 their opposite ends respectively provided with headers 34 and 35 which are connected with each other through the agency of the tubes 36 which provide water passages. These water passages are elongated in cross 60 section and have the cooling fins 37 arranged transversely thereof. The header 34 which is adapted to be connected with the tank 14 is provided with one or more apertures 38, the apertures being designed to communicate 65 with apertures such as 33 provided in the tubular extensions 32 of the tank 14. A gas-

ket 39 is arranged between the tubular extension 32 and the header 34 and said header and tank 14 are held in associated relation with each other through the agency of bolts such as 40 which extend through the tubular extension 32, the apertures 33 and 38 into connection with a spider 41, the spider being provided with an internally threaded collar 42 for the reception of the threaded end of the bolt 40. It is manifest that 70 this provides a means whereby the tank 14 and the adjacent end of the heat exchange devices such as 31 are connected and held in associated relation with each other, the connection permitting circulation of water from 75 the tank 14 through the apertures 33 and 38 into the header 34, from which the water gravitates through the tubular ducts 36 into the header 35 and thence through the pipe connection 43, it being understood that each 80 of the heat exchange devices 31 are provided with a pipe connection such as 43 and that these pipe connections 43 are, in turn, connected with the return pipe 16 which, as before stated, connects with the water jacket 85 of the motor. The headers 35 of each of the heat exchange devices 31 are supported through the agency of brackets respectively designated 44 and 45, the bracket 44 being connected with an angle iron base or support 90 95 46 which may be secured to the roof of the conveyance. This angle iron support 46 also provides a means to which the end wall 47 may be attached. The end wall together with the side walls 48 and 49 provide a compartment or housing for the several heat exchange devices 31, it being understood that the bracket 45 is connected with the end wall 47 and thus with the bracket 44 provides a 100 means for supporting the adjacent ends of 105 the respective heat exchange devices.

The side plates 48 and 49 and the end plate 47 are secured to a frame including the angle iron elements 50, 51, 52 and 53 which are connected at their forward ends to the transversely arranged angle iron members 54 and 56. The side walls 48 and 49 are provided with the outwardly extending flanges 55 and 56 which are, in turn, bolted to the vertically arranged standards or supports respectively 110 designated 57 and 58. These standards or supports 57 and 58 also support the tank 14. The housing 29 for the motor 28 is and the fans 26 and 27 are connected with the standards 57 and 58. The radiators or heat 115 exchange devices 20, 21, 22 and 23 form ends for the housing, the heat exchange devices being separated from each other to provide spaces 61 and 62 through which air may travel relatively to the housing. These heat exchange devices 20 to 23 include headers 63 and 64 located adjacent the opposite ends of the heat exchange devices and each of these headers has a pipe connection 65 and a pipe 120 connection 66 extending therefrom, the 125

former being connected with the lubricant conduit 18, the pipe connections 66 being connected with the return pipe 24 and the passage 25 to return the cooled lubricant to the engine after it is passed through the heat exchange devices 20 to 23. These heat exchange devices substantially correspond in construction with the heat exchange devices 31 and thus include a plurality of tubular passages 67 and transversely arranged fins 68, the opposite ends of the tubes 67 being respectively connected with relatively thin plates 69 and 70 which respectively form closures for the headers 63 and 64. These plates 69 and 70 and also the corresponding plates of the heat exchange devices 31 are provided with longitudinally extending flanges 71 which are inserted in grooves 72 formed in the parts 63 and 64 providing the headers, 10 are brazed or otherwise secured to these portions and permit linear extension of the tubes without causing a break or leak between the plates such as 70 and the header with which they are connected.

25 The headers 63 and 64 are respectively provided with an angle iron bracket 73 and 74, the bracket 73 being attached to an angle iron frame member 75 which extends from the angle iron uprights 76 to the supports 57 and 58. The lower ends of the heat exchange devices 20 to 23 are supported through the agency of an angle iron base member 77 having an angular iron bracket element 78 suitably secured thereto to provide a connection with the angle iron bracket 74, these last mentioned parts being held in associated relation through the agency of any suitable means such as the bolts 79.

40 The fans 26 and 27 are arranged to rotate in a housing formed by the top wall 59, the side wall 60 (see Fig. 7) the roof of the vehicle and a wall such as 80, it being understood that each end of the housing generally designated 29 is provided with a wall such as 80. These walls are supported at their innermost ends by an annular reenforcing band 81 which connects these walls and the wall such as 60. From this it can be seen that upon rotation of the fans air is drawn through the open side 50 of the casing 12, the heat exchange devices generally designated 15, through said devices into the housing generally designated 29 in which the fans are located, and thence caused to flow through the opposite ends of this last mentioned housing and through the heat exchange devices respectively designated 20 to 23 which will subject the cooling fluid for the engine and also the oil or lubricant therefor to the cooling effect of the air currents produced by the fans. It is evident that as the water and lubricant of the motor become heated it rises, flows through the respective heat exchange devices and is returned in a cooled condition to the motor.

55 An arrangement such as this permits the engine to be operated at higher speeds than heretofore without resulting in excessive wear of the moving parts of the engine and will thus add life to the engine. If so desired, a plate 82 may be arranged in the housing for the heat exchange device generally designated 15, the plate being provided to direct air currents entering the housing and insure their passing through the heat exchange device generally designated 15 before they enter the fan housing.

70 The modified structure shown in Figs. 10 and 11 contemplates the utilization of a motor 83, fans 84 and 85 which are driven by the motor, heat exchange devices 86 and transversely arranged heat exchange devices 87, 88, 89 and 90. The heat exchange devices 86 are connected with a tank 91 and are each provided with an outlet pipe connection 92 in a manner and for a purpose similar to that described in connection with the structure shown in Fig. 1. The structure shown in Figs. 10 and 11 differs from the structure shown in Fig. 1 in that the heat exchange devices 86 are arranged relatively to a casing 93 to form a closure for an open side of the casing, the heat exchange devices 87 to 90 being disposed relatively to the heat exchange devices 86 to provide part of a side wall of the casing 93, the casing being completed through the agency of plates such as 94 and 95 and an end plate 96, it being understood that the opposite sides of the casing 93 are provided with plates such as 94 and 95 to complete the housing. The heat exchange devices 87 to 90 are each provided with an inlet 97 and an outlet 98 to thus permit a circuit to be completed between these devices and the engine, the lubricant of which it is desired to cool. The side plates 94 and 95 are arranged on opposite sides of the housing and the end plate 96 are held in associated relation by being connected with a supporting frame 99 therefor which, as clearly shown in Fig. 10, is connected to uprights or supports 100 such as those previously described in connection with the structure illustrated in Fig. 1.

75 The fans 26 and 27 are arranged to rotate in a housing formed by the top wall 59, the side wall 60 (see Fig. 7) the roof of the vehicle and a wall such as 80, it being understood that each end of the housing generally designated 29 is provided with a wall such as 80. These walls are supported at their innermost ends by an annular reenforcing band 81 which connects these walls and the wall such as 60. From this it can be seen that upon rotation of the fans air is drawn through the open side 80 of the casing 12, the heat exchange devices generally designated 15, through said devices into the housing generally designated 29 in which the fans are located, and thence caused to flow through the opposite ends of this last mentioned housing and through the heat exchange devices respectively designated 20 to 23 which will subject the cooling fluid for the engine and also the oil or lubricant therefor to the cooling effect of the air currents produced by the fans. It is evident that as the water and lubricant of the motor become heated it rises, flows through the respective heat exchange devices and is returned in a cooled condition to the motor.

85 An arrangement such as this permits the engine to be operated at higher speeds than heretofore without resulting in excessive wear of the moving parts of the engine and will thus add life to the engine. If so desired, a plate 82 may be arranged in the housing for the heat exchange device generally designated 15, the plate being provided to direct air currents entering the housing and insure their passing through the heat exchange device generally designated 15 before they enter the fan housing.

90 The modified structure shown in Figs. 10 and 11 contemplates the utilization of a motor 83, fans 84 and 85 which are driven by the motor, heat exchange devices 86 and transversely arranged heat exchange devices 87, 88, 89 and 90. The heat exchange devices 86 are connected with a tank 91 and are each provided with an outlet pipe connection 92 in a manner and for a purpose similar to that described in connection with the structure shown in Fig. 1. The structure shown in Figs. 10 and 11 differs from the structure shown in Fig. 1 in that the heat exchange devices 86 are arranged relatively to a casing 93 to form a closure for an open side of the casing, the heat exchange devices 87 to 90 being disposed relatively to the heat exchange devices 86 to provide part of a side wall of the casing 93, the casing being completed through the agency of plates such as 94 and 95 and an end plate 96, it being understood that the opposite sides of the casing 93 are provided with plates such as 94 and 95 to complete the housing. The heat exchange devices 87 to 90 are each provided with an inlet 97 and an outlet 98 to thus permit a circuit to be completed between these devices and the engine, the lubricant of which it is desired to cool. The side plates 94 and 95 are arranged on opposite sides of the housing and the end plate 96 are held in associated relation by being connected with a supporting frame 99 therefor which, as clearly shown in Fig. 10, is connected to uprights or supports 100 such as those previously described in connection with the structure illustrated in Fig. 1.

95 The fans 26 and 27 are arranged to rotate in a housing formed by the top wall 59, the side wall 60 (see Fig. 7) the roof of the vehicle and a wall such as 80, it being understood that each end of the housing generally designated 29 is provided with a wall such as 80. These walls are supported at their innermost ends by an annular reenforcing band 81 which connects these walls and the wall such as 60. From this it can be seen that upon rotation of the fans air is drawn through the open side 100 of the casing 12, the heat exchange devices generally designated 15, through said devices into the housing generally designated 29 in which the fans are located, and thence caused to flow through the opposite ends of this last mentioned housing and through the heat exchange devices respectively designated 20 to 23 which will subject the cooling fluid for the engine and also the oil or lubricant therefor to the cooling effect of the air currents produced by the fans. It is evident that as the water and lubricant of the motor become heated it rises, flows through the respective heat exchange devices and is returned in a cooled condition to the motor.

100 The fans 26 and 27 are arranged to rotate in a housing formed by the top wall 59, the side wall 60 (see Fig. 7) the roof of the vehicle and a wall such as 80, it being understood that each end of the housing generally designated 29 is provided with a wall such as 80. These walls are supported at their innermost ends by an annular reenforcing band 81 which connects these walls and the wall such as 60. From this it can be seen that upon rotation of the fans air is drawn through the open side 105 of the casing 12, the heat exchange devices generally designated 15, through said devices into the housing generally designated 29 in which the fans are located, and thence caused to flow through the opposite ends of this last mentioned housing and through the heat exchange devices respectively designated 20 to 23 which will subject the cooling fluid for the engine and also the oil or lubricant therefor to the cooling effect of the air currents produced by the fans. It is evident that as the water and lubricant of the motor become heated it rises, flows through the respective heat exchange devices and is returned in a cooled condition to the motor.

110 The fans 26 and 27 are arranged to rotate in a housing formed by the top wall 59, the side wall 60 (see Fig. 7) the roof of the vehicle and a wall such as 80, it being understood that each end of the housing generally designated 29 is provided with a wall such as 80. These walls are supported at their innermost ends by an annular reenforcing band 81 which connects these walls and the wall such as 60. From this it can be seen that upon rotation of the fans air is drawn through the open side 110 of the casing 12, the heat exchange devices generally designated 15, through said devices into the housing generally designated 29 in which the fans are located, and thence caused to flow through the opposite ends of this last mentioned housing and through the heat exchange devices respectively designated 20 to 23 which will subject the cooling fluid for the engine and also the oil or lubricant therefor to the cooling effect of the air currents produced by the fans. It is evident that as the water and lubricant of the motor become heated it rises, flows through the respective heat exchange devices and is returned in a cooled condition to the motor.

115 The fans 26 and 27 are arranged to rotate in a housing formed by the top wall 59, the side wall 60 (see Fig. 7) the roof of the vehicle and a wall such as 80, it being understood that each end of the housing generally designated 29 is provided with a wall such as 80. These walls are supported at their innermost ends by an annular reenforcing band 81 which connects these walls and the wall such as 60. From this it can be seen that upon rotation of the fans air is drawn through the open side 115 of the casing 12, the heat exchange devices generally designated 15, through said devices into the housing generally designated 29 in which the fans are located, and thence caused to flow through the opposite ends of this last mentioned housing and through the heat exchange devices respectively designated 20 to 23 which will subject the cooling fluid for the engine and also the oil or lubricant therefor to the cooling effect of the air currents produced by the fans. It is evident that as the water and lubricant of the motor become heated it rises, flows through the respective heat exchange devices and is returned in a cooled condition to the motor.

120 The fans 26 and 27 are arranged to rotate in a housing formed by the top wall 59, the side wall 60 (see Fig. 7) the roof of the vehicle and a wall such as 80, it being understood that each end of the housing generally designated 29 is provided with a wall such as 80. These walls are supported at their innermost ends by an annular reenforcing band 81 which connects these walls and the wall such as 60. From this it can be seen that upon rotation of the fans air is drawn through the open side 120 of the casing 12, the heat exchange devices generally designated 15, through said devices into the housing generally designated 29 in which the fans are located, and thence caused to flow through the opposite ends of this last mentioned housing and through the heat exchange devices respectively designated 20 to 23 which will subject the cooling fluid for the engine and also the oil or lubricant therefor to the cooling effect of the air currents produced by the fans. It is evident that as the water and lubricant of the motor become heated it rises, flows through the respective heat exchange devices and is returned in a cooled condition to the motor.

125 The fans 26 and 27 are arranged to rotate in a housing formed by the top wall 59, the side wall 60 (see Fig. 7) the roof of the vehicle and a wall such as 80, it being understood that each end of the housing generally designated 29 is provided with a wall such as 80. These walls are supported at their innermost ends by an annular reenforcing band 81 which connects these walls and the wall such as 60. From this it can be seen that upon rotation of the fans air is drawn through the open side 125 of the casing 12, the heat exchange devices generally designated 15, through said devices into the housing generally designated 29 in which the fans are located, and thence caused to flow through the opposite ends of this last mentioned housing and through the heat exchange devices respectively designated 20 to 23 which will subject the cooling fluid for the engine and also the oil or lubricant therefor to the cooling effect of the air currents produced by the fans. It is evident that as the water and lubricant of the motor become heated it rises, flows through the respective heat exchange devices and is returned in a cooled condition to the motor.

130 The fans 26 and 27 are arranged to rotate in a housing formed by the top wall 59, the side wall 60 (see Fig. 7) the roof of the vehicle and a wall such as 80, it being understood that each end of the housing generally designated 29 is provided with a wall such as 80. These walls are supported at their innermost ends by an annular reenforcing band 81 which connects these walls and the wall such as 60. From this it can be seen that upon rotation of the fans air is drawn through the open side 130 of the casing 12, the heat exchange devices generally designated 15, through said devices into the housing generally designated 29 in which the fans are located, and thence caused to flow through the opposite ends of this last mentioned housing and through the heat exchange devices respectively designated 20 to 23 which will subject the cooling fluid for the engine and also the oil or lubricant therefor to the cooling effect of the air currents produced by the fans. It is evident that as the water and lubricant of the motor become heated it rises, flows through the respective heat exchange devices and is returned in a cooled condition to the motor.

rangement which may be employed. This structure contemplates the use of a casing 105, fans 106 and a heat exchange device 107. In the structure the side walls of the casing 105 are extended beyond the heat exchange device 107 and provide supports for the vanes 108 which extend transversely across the heat exchange device 107 and provide means for protecting and directing air toward this heat exchange device arranged within the casing. It is manifest that depending upon the direction of rotation of the fans, that air may be drawn through either set of heat exchange devices into the fan housing and be expelled therefrom. It is also evident that the structure forms an efficient arrangement which will quickly and effectively cool both the lubricant for the engine and the cooling medium and accomplish cooling of relatively large quantities of these commodities.

It is understood that the structure of the heat exchange devices shown in Figs. 10 and 11 corresponds with the structure of these same devices employed in the previously described structure, in that the structure connected with the tubular elements permits the tubular elements to expand and contract without causing breakage and leakage.

Having thus described my invention, what I claim as new and desire to secure by Letters Patent is:

1. In a device of the kind described the combination of a casing, heat exchange devices providing top and side walls of said casing, the top wall being inclined to the horizontal, a motor and fan located at one end of said casing and at one end of said inclined heat exchange device and providing means for circulating air through said heat exchange devices and casing.

2. In a device of the kind described the combination of a casing, heat exchange devices providing side walls of said casing, air advancing means located adjacent said heat exchange devices and a heat exchange device providing a top wall of said casing projecting laterally from said first mentioned heat exchange devices.

3. In a device of the kind described the combination of a casing, heat exchange devices providing side walls of said casing, air advancing means located adjacent said heat exchange devices and a heat exchange device providing a top wall of said casing having one edge arranged adjacent said first mentioned heat exchange devices and projecting in a lateral and downwardly direction therefrom.

4. In a device of the kind described the combination of a casing, heat exchange devices providing side walls of said casing, a heat exchange device having fluid passages arranged transversely to the passages of said first mentioned heat exchange devices and projecting from said first mentioned heat ex-

change devices and providing another wall of said casing and air advancing means located in said casing for advancing air through said heat exchange devices.

5. In a device of the kind described the combination of a casing, a plurality of heat exchange devices one of which is located between a pair of said devices respectively, said devices providing side and top walls of said casing, air advancing means including a motor the axis of which is located transversely of the length of said casing and providing means for advancing air through said heat exchange devices and casing.

6. In a device of the kind described, the combination of a casing, a plurality of heat exchange devices, one of which is located between a pair of said devices, said devices respectively providing top and side walls of said casing, air advancing means including a motor, the axis of which is arranged transverse of the length of the casing, said air advancing means having an element thereof located at each of said heat exchange devices providing said side walls.

7. In a device of the kind described the combination of a plurality of heat exchange devices respectively providing top and side walls of a casing, said heat exchange device providing said top wall being located between said devices providing the side walls, air advancing means respectively rotatable in planes parallel with said heat exchange devices providing said side walls for advancing air through said plurality of heat exchange devices.

8. In a device of the kind described the combination of a plurality of heat exchange devices respectively providing side and top walls of a casing, one of said heat exchange devices being located between said devices providing said side walls and projecting laterally therefrom and being inclined to the horizontal, air advancing means respectively rotatable in planes parallel with said heat exchange devices providing said side walls for advancing air through said plurality of heat exchange devices.

9. In a device of the kind described the combination of a plurality of heat exchange devices respectively providing top and side walls of a casing, means for advancing air through said casing, a fluid supply tank with which said device providing the top wall is connected.

In witness whereof, I hereunto subscribe my name this 30th day of September A. D. 1929.

ARTHUR B. MODINE.
